DESIGN FOR A JAM DISH

Jean O. Reinecke and James F. Barnes, Chicago,
Ill., assignors to McGraw Electric Company,
Chicago, Ill., a corporation of Delaware

Application August 15, 1938, Serial No. 79,357

Term of patent 7 years

To all whom it may concern:

Be it known that we, Jean O. Reinecke and James F. Barnes, citizens of the United States, both residing at Chicago, in the county of Cook and State of Illinois, have invented a new, original, and ornamental Design for a Jam Dish, of which the following is a specification, reference being had to the accompanying drawing, forming part thereof, in which

Fig. 1 is a top plan view of a jam dish showing our new design,

Fig. 2 is a view in side elevation thereof, and
Fig. 3 is a sectional view therethrough, taken on the line 3—3 of Fig. 1.

We claim:

The ornamental design for a jam dish, as shown and described.

JEAN O. REINECKE.
JAMES F. BARNES.
